UNITED STATES PATENT OFFICE.

FRANK J. MULDOON, OF WEST BEND, WISCONSIN, ASSIGNOR OF ONE-HALF TO HENRY LOCHEN, OF WEST BEND, WISCONSIN.

IRONING-TABLE.

1,091,006.

Specification of Letters Patent. Patented Mar. 24, 1914.

Application filed September 28, 1912. Serial No. 722,895.

To all whom it may concern:

Be it known that I, FRANK J. MULDOON, a citizen of the United States, and resident of West Bend, in the county of Washington and State of Wisconsin, have invented certain new and useful Improvements in Ironing-Tables; and I do hereby declare that the following is a full, clear, and exact description thereof.

10 My invention consists in what is herein particularly set forth with reference to the accompanying drawings and pointed out in the claim of this specification, its object being to provide simple, economical and efficient anti-marring clamping mechanism in connection with ironing-tables for detachable connection with other tables, shelves or the like, said mechanism having certain advantageous features of construction.

20 Figure 1 of the drawings represents a side elevation of one of my improved ironing-tables partly broken away and set up in detachable connection with another table; Fig. 2, a plan view of the same partly broken away, this view being indicated by line 2—2 in Fig. 1; Fig. 3, a section view of a detail of the ironing-table indicated by line 3—3 in Fig. 1, and Fig. 4, a detail inverted plan view of an iron-holder attachment of said ironing-table partly in horizontal section on the plane indicated by line 4—4 in Fig. 1.

25 Referring by numerals to the drawings, 5 indicates a board that constitutes the top of my improved table especially designed to facilitate the ironing of skirts and sleeves, the board being narrowed at one end to form a sleeve-holder 5'. The other end of the board is provided with a central longitudinal slot 6, for the reception of a leg 7 pivotally arranged between a pair of parallel strips 8 secured longitudinally to the underside of said board to which they impart rigidity, the pivot being preferably a bolt 9 having a nut 10 run thereon against a washer.

30 The leg 7 is provided with a longitudinal slot 11 adjacent to what is its upper end when the table is set up, and extending through this slot is a carriage bolt 12 having the angular portion thereof, adjacent to its head, engaged with a corresponding open-

ing in a clamping-shell 13 for which it constitutes a shank, the shell being elliptical or otherwise curvilinear in cross-section. The 55 shell is non-rotary on the bolt and at right angles to the leg 7 and said shell is provided with an under clearance aperture for the bolt-head. It is also preferably covered with rubber, felt or other anti-marring material 14, and the upper side of the slotted broad end of the board 5 is also preferably faced with similar material 15. Run on the screw-threaded outer end of the bolt 12 against a washer 16, opposing the leg 7, is a 60 thumb-nut 17, and by the adjustment of said bolt in the slot 11 the angle of the leg 7 with reference to the height of a table 18, shelf or other support for the ironing table is determined, said support being caught 65 between the board 5 and clamping shell 13.

Extending through the leg 7 outward from its slot 11, is a preferably collared pivot-pin 19 for arms 20 of an iron-holder 21 having a leg 22 that rests upon the leg 75 aforesaid when said holder is in working position, as shown in Fig. 1. The iron holder is preferably a sheet of metal suitably slotted to provide its arms 20 and leg 22 that are bent out therefrom, as shown, 80 the free ends of said arms being turned to form pivot-pin eyes and said leg suitably bent. When not in use the iron-holder is swung back on the pivot-pin 19 out of the way, and when the table is folded its leg 7 85 is parallel to the board 5 between the strips 8 thereon.

My improved ironing-table has a very tight anti-marring grip upon the table 18 or other support and is not liable to lateral 90 play, while at the same time the board thereof is very rigid outward from the pivotal leg, the position of said leg, when said table is in use, being such as to afford ample clearance for a skirt being ironed upon said 95 board.

I claim:

In a folding ironing-table of the type comprising a board and a pivotal center leg which leg extends obliquely above the board 100 when the table is set up, the combination with the leg of a bolt extending through a longitudinal slot of the same adjacent to said end thereof, a clamping-nut on the

outer end of the bolt, and a shell non-rotary on said bolt under said leg at right-angles thereto, the shell being curvilinear in cross-section and provided with an under clearance aperture for the head of said bolt.

In testimony that I claim the foregoing I have hereunto set my hand at West Bend

in the county of Washington and State of Wisconsin in the presence of two witnesses.

FRANK J. MULDOON.
